AIR GUN NOZZLE

James E. Mortimore, Stratford, Conn.

Application July 8, 1955, Serial No. 36,870

Term of patent 14 years

(Cl. D62—2)

Fig. 1.

Fig. 2.

Fig. 3.

Fig. 4.

Fig. 1 is a side elevation of the air gun nozzle showing my new design;

Fig. 2 is a front elevation;

Fig. 3 is a top plan view; and

Fig. 4 is a rear elevation.

The other side of my new air gun nozzle shown in Fig. 1 is substantially the same as the side shown.

I claim:

The ornamental design for an air gun nozzle, substantially as shown and described.
